UNITED STATES PATENT OFFICE.

THOMAS J. MURPHY AND EDWARD MILLER, OF ROCHESTER, NEW YORK.

CALL SYSTEM.

1,231,537.

Specification of Letters Patent. Patented June 26, 1917.

Application filed July 17, 1916. Serial No. 109,689.

To all whom it may concern:

Be it known that we, THOMAS J. MURPHY, a subject of the King of Great Britain, and EDWARD MILLER, a citizen of the United States, residents of Rochester, in the county of Monroe and State of New York, have invented a certain new and useful Call System; and we do hereby declare the following to be a full, clear, and exact description of the invention, such as will enable others skilled in the art to which it appertains to make and use the same, reference being had to the accompanying drawings, and to the characters of reference marked thereon, which form a part of this specification.

Our invention relates to call systems and it has for its object to provide a simple call system which will indicate upon calling whether the party called is in position to receive the call.

By our invention signaling devices are located at the calling and at the called station and are each controlled by a switch located preferably at the station called, other than the one at which the calling device is located. The invention is dependent upon the rise in resistance of the tungsten filament, due to increased temperature, it having a low initial resistance when cold.

Referring to the figures wherein are shown a system involving our invention and devices that may be used in connection therewith, Figure 1 illustrates a front view or cover plate for push button and lamp. Fig. 2 illustrates a shell or housing which may be secured in a recess formed in a wall. Fig. 3 is a sectional view taken on the line 3-3 indicated in Fig. 2. Fig. 4 is a diagram of the connections of the parts of the system. Fig. 5 is a plate used in a modification of the system shown in Fig. 1. Fig. 6 is a view of a shell or housing. Fig. 7 is a sectional view taken on the line 7-7 indicated in Fig. 6. Fig. 8 is a section of a part of a structure illustrated in Figs. 1, 5 and 7 and is a view taken on the line 8-8 indicated in Fig. 5. Fig. 9 is a diagram showing connections between the parts of the modified system.

Fig. 1, Fig. 1, is a front or covering plate which covers a shell or housing 2, which

may be located in a recess of a wall. The cover plate 1 is secured to the wall by means of screws 3 and thereby locks the housing 2 in a recess that may be cut into the wall. 55

The plate 1 is provided with an opalescent glass 5, which may be secured in the plate 1 in any suitable way. The plate 1 is also provided with a short sleeve 6 in which a push button 7 may be inserted. The push 60 button 7 may be provided with a flange 8 which is pressed against the inner end of the cylinder 6 by means of one of the spring contacts that is operated by the push button in the manner well known in the art. The 65 housing 2 is provided with an inturned lip 10 at each end of the housing which fits the bevel 11 of the ends of the plate 1 on the under side of the plate 1 so that when the plate 1 is placed against the housing 2 the 70 plate 1 operates to hold the housing in somewhat definite relation to the plate 1.

The housing 2 is also provided with lateral extending flanges 12 to which may be secured, if desired, rings 13, as shown in 75 Fig. 8, which are located on the plate 1. The ground glass lenses 5 may be secured in the rings 13 and the rings 13 may be secured to the housing 2 by means of screws 14 which also operate to clamp the plate 1 80 in a definite position relative to the housing 2.

The housing 2 is also provided with a lamp 20 having a tungsten filament 21. The lamp is secured in a suitable socket 22 85 and is insulatingly supported in the interior of the housing 2, suitable means being provided for connecting the lamp 20 with an external circuit such as by the pin 23. The lamp 20 is located in proximity to the 90 opalescent lens 5 and so as to illuminate the same when the lamp is lighted.

The push button 7 operates upon the spring contacts 25 so as to close the said contacts. The contacts are supported and connected to an external circuit by means of the pins 23 and 28. If desired, the housing may be provided with insulating sheets 29 and 30, which cover the bottom of the housing or shell on the inside and on the 100 outside for insulating purposes.

As shown in the diagram of Fig. 4 of the

drawing, the battery 35 is connected on one side to one of the contacts 25 and on the other side to a vibrator 36 of the well known type, which makes and breaks the circuit in which it is connected in its operation. It is also connected to a resistance 37 located in a shunt circuit which is closed and opened by means of the switch 38. The vibrator and switch 38 are connected to the lamp 20 and the lamp 20 is connected to the remaining contact 25.

In operation the system is in calling condition whether the switch 38 is open or closed. When the button 7 is pressed to complete the circuit of the battery it will pass through the filament of the lamp 20 and the vibrator 36 and will ring a loud, clear call, but inasmuch as the current is interrupted, opportunity will not be given for the current to visually affect the filament of the lamp and consequently the lamp will not be lighted. On the other hand, if the system is placed in feeble ringing condition, as when the party at the called station leaves the station, the switch 38 is closed so as to close the shunt having the resistance 37, and if then the push button 7 is pressed the shunt circuit will allow a continuous current to pass through the filament of the lamp 20 and will become lighted. This will put the system in feeble ringing condition, indicating at station called the condition of the system.

In the form of the system illustrated in Fig. 9, having the parts illustrated in Figs. 5, 6 and 7, the covering plate 40 is provided with two opalescent glasses, one of which is shown at 41, the figure showing the other one as being removed for purposes of illustration. The opalescent glasses are located at the ends of the plate 40 and the push button 42 is located centrally with respect to the plate 40 and between the lenses 41. A housing 43 is provided with two lamps 44 and 45, which are secured in sockets 46 and 47. They are suitably secured in the housing 43. The push button 42 operates to close the spring contacts 49. Means are provided for connecting the lamps and the contacts with an external circuit in any suitable manner. As shown in the diagram of Fig. 9, the battery 51 is connected to one of the contacts 49 on one side and to a vibrator 55 on the other side. A switch arm 56 is connected to the vibrator. The switch arm 56 is made so as to bridge either pair of contacts 57 or 58 when the switch 56 is thrown in one direction or the other. The switch contact 56 bridges lower contact 57 and lower contact 58 simultaneously, to prevent having the bell on open circuit. The lower contacts are connected to a resistance 59 which will then be connected in shunt with the vibrator 55. The lower one of the contacts 57 is connected to the lamp

44 and the lower one of the contacts 58 is connected to the lamp 45, and the lamps 44 and 45 are connected to the remaining contact 49. In the operation the switch 56 is placed either on one pair 57 or on the other pair 58, of contacts, and when the push button 42 is pressed so as to close the circuit through the contacts 49 the current will pass either through the lamp 44 or the lamp 45 and the pair of contacts 57 or 58, according to the position of the switch 56. This will cause the current to divide at this point, part of which will pass through the vibrator 55 and a part through the resistance 59 to the battery 51. This will cause one or the other of the lamps 44 or 45 to become lighted and also cause the bell 55 to ring feebly. The lamps 44 and 45, depending on which one is lighted, will indicate to the operator whether or not the called party has received the call, for if he is in the switch 56 having contact 70 will be placed so as to complete the circuit to the contacts 57, which will cause the lamp 44 to be lighted, and when he goes out, or at will, he will throw the switch 56 so as to complete the circuit to the contacts 58, which will cause the lamp 45 to become lighted when the push button 42 is pressed.

The invention may be modified by those skilled in the art without departing from the spirit thereof.

Having thus described our invention, what we claim as new and desire to secure by Letters Patent, is,

1. In a call system, the combination of a source of current supply, a circuit closer and a lamp located at a calling station, a vibrator signaling device located in series with the lamp and the circuit closer, a resistance connected in shunt with the vibrating signaling device and a switch for opening and closing the circuit through the resistance, the vibrating signaling device, the resistance and the switch located at a station to be called to cause the lamp to become lighted when the circuit closer and the switch are closed and to cause the operation of the vibrating signaling device and to prevent the lighting of the lamp when the circuit closer is closed and the switch is open.

2. In a call system, the combination of a source of current supply, a circuit closer, a lamp having a tungsten filament and a vibrator signaling device located in series, a resistance connected in shunt to the vibrator signaling device, a switch for opening and closing the circuit through the resistance to cause the lamp to become lighted and to prevent the operation of the vibrator signaling device when the circuit closer and the switch are closed, and to cause the operation of the vibrating signaling device and to prevent the lighting of the lamp when the circuit closer is closed and the switch is open.

3. In a call system, the combination of a source of current supply, a vibrator signaling device and a circuit closer, a pair of lamps having tungsten filaments located in 5 parallel circuits, a resistance located in a circuit in shunt to the vibrator signaling device, a switch for connecting either lamp

with the resistance and the vibrator signaling device.

In testimony whereof, we have hereunto signed our names to this specification.

THOMAS J. MURPHY.
EDWARD MILLER
